UNITED STATES PATENT OFFICE.

GERHARD COENEN, OF JERSEY CITY, NEW JERSEY.

ANTIFREEZING FLUSHING-TANK.

No. 800,903.

Specification of Letters Patent.

Patented Oct. 3, 1905.

Application filed November 28, 1904. Serial No. 234,461.

To all whom it may concern:

Be it known that I, GERHARD COENEN, a subject of the German Emperor, residing in Jersey City, in the county of Hudson and State of

5 New Jersey, have invented certain new and useful Improvements in Antifreezing Flushing-Tanks; and I do hereby declare the following to be a full, clear, and exact description of the invention, such as will enable others skilled in 10 the art to which it appertains to make and use the same, reference being had to the accompanying drawings, and to letters of reference marked thereon, which form a part of this specification.

15 My invention relates to flushing apparatus, and particularly to flushing apparatus in which a tank is employed to hold the water for flushing; and it has for its object to provide an apparatus of this kind in which the tank will be 20 normally empty, being only supplied with the water for flushing just before use, and to do away with the means now commonly employed for starting the flushing which requires the user's attention in order that it be operated.

25 In the accompanying drawings, Figure 1 is a front view of my apparatus, showing certain parts in section; and Fig. 2 shows the valve for controlling the water-supply.

In said drawings, *a* is a supply-pipe; *b*, the 30 bowl of the closet; *c*, the seat, and *d* a valve located in said pipe and of that well-known type wherein a spring-actuated valve proper, *e*, normally closes off the way through pipe *a* and only opens said way when actuated by the 35 application of sufficient force against the seat, which when down rests upon its stem *f*. Said valve *d* also has a drain-opening *g*, discharging into the bowl *b* and so controlled by the valve proper, *e*, that it is closed by said valve 40 when the way is open through pipe *a*, but open to drain off the water in pipe *a* above valve *d* when valve proper, *e*, is closed.

h is the flush tank or cistern, which latter is adapted to discharge into the bowl through 45 the usual flush-pipe *i*. The coupling *j*, whereby said flush-pipe is connected with the bottom of the tank, comprises a funnel-shaped valve-chamber *k*, whose flaring end opens into the tank.

50 *l* is a valve adapted to seat in valve-chamber *k* to cut off the discharge of water from the tank into pipe *i*. For a reason hereinafter explained it is preferable that this be a buoyant body, and its lower end is made frustoconical, so as to fit into the flaring portion of the valve-chamber *k*, the proper seating of

the valve being always insured by a tubular projection *m* on its lower end which extends into the valve-chamber and has one or more ports *n*.

60 *o* is a cylinder which is closed at the top by a cap *p* and which forms, in effect, the upper termination of pipe *a*. Said cylinder and pipe *a* are connected together and fixed in the tank-bottom by a coupling *q*. Attached to the side 65 of said cylinder is the usual discharge-valve *r* for the pipe *a*, the said valve being under the control of a float *s*, which when raised upon the filling of the tank closes said valve *r* and when allowed to fall to the bottom of 70 the tank upon the emptying of the latter opens the valve. In the cylinder *o* is a piston *t*, which is pressed downwardly by a spiral spring *t'*, coiled in the cylinder between said piston and the cap *p* and which has a stem *u* 75 projecting up through the cap. The upper end of the piston *t* and the upper end of the valve *l* are pivotally connected to a lever *v* on opposite sides of its fulcrum *w*, which latter is in a bracket *x*, attached to the tank.

80 In operation when valve *d* is actuated by pressure exerted on seat *c* the water-pressure comes directly on the piston *t*, which rises and through lever *v* depresses valve *l* and, causes it to seat, and thus cut off the discharge 85 from the tank. The tank is assumed to be empty, so that float *s* is down and the valve *r* open to admit the water from pipe *a* to the tank. The tank now fills until the float rises sufficiently so that valve *r* is made to cut off 90 the water-supply from pipe *a*. Upon the pressure now being withdrawn from seat *c* valve *d* will close and cut off the pressure, at the same time permitting the water in pipe *a* above valve *l* to drain off into the bowl 95 through opening *g*. The spring *t'*, which has up to this time been compressed by the water-pressure forcing up the piston *t*, now forces the piston down, which action causes the valve *l* to be lifted through lever *v*, and so open the 100 discharge from the tank through the flushing-pipe, leaving the tank empty and the whole apparatus in condition for a repetition of the operation. The buoyancy of the valve assists the spring *t'* in making the discharge of the 105 tank prompt and sure. Valve *d*, it will be observed, not only permits the draining of pipe *a*, so that said pipe, as well as the tank, is normally free of water, and thus proof against freezing, but provides a quick relief for the 110 water in pipe *a* above it, so that the piston may descend and thus permit valve *l* to rise.

quickly, whereby a precipitate discharge of the tank results.

Having thus fully described my invention, what I claim as new, and desire to secure by 5 Letters Patent, is—

The combination of a water-supply pipe, a tank having a discharge-outlet, said pipe being connected with the tank, a float-controlled discharge-valve for said pipe located in the 10 tank, another valve, located outside of said tank, controlling the passage of water through said pipe, another valve controlling the outlet of said tank, controlling means for said last-named valve, said means being normally

adapted to open said valve and being actuated 15 by the pressure of water admitted through said pipe to close said valve, and means for effecting the release of water in said pipe between said second-named valve and the controlling means after the closing of said valve, 20 substantially as described.

In testimony that I claim the foregoing I have hereunto set my hand this 1st day of November, 1904.

GERHARD COENEN.
